UNITED STATES PATENT OFFICE.

JOHN WINKLER, OF PHILADELPHIA, PENNSYLVANIA.

PERMUTATION VAULT LOCK.

Application filed March 14, 1925. Serial No. 15,446.

To all whom it may concern:

Be it known that I, JOHN WINKLER, a citizen of the United States, and residing in Philadelphia, in the county of Philadelphia and State of Pennsylvania, have invented a new and useful Permutation Vault Lock, of which the following is a specification.

My invention relates to a new and useful improvement in permutation locks for vault doors and the like, adapted to be locked and unlocked by means of a novel permutation device without the aid of any key.

My invention further relates to a novel lock of the character stated, which may be so interlocked and interlinked with another, or similar locks, on the same door, as to provide an operative interengagement of the two at all times, whereby one may not be released without releasing each of other locks on the door.

With the above ends in view, my invention consists of bolts slidably mounted near, and at right angles to the edge of the door, a plurality of rotary locking tumblers mounted within the door, adapted positively to retain said bolts, and a common actuating device for each of said bolts, for moving said bolts inwardly or outwardly simultaneously, so as to lock said door at a plurality of points. My invention further consists of other instrumentalities and novel details of construction as will be more fully described in the claims appended hereto.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Referring to the drawings in which like reference characters indicate like parts:

Fig. 1 represents a front elevation of a vault door embodying my invention.

Fig. 2 represents a rear elevation of the same.

Fig. 3 represents a section on line 3—3 of Fig. 1.

Fig. 4 represents a section on line 4—4 of Fig. 3.

Fig. 5 represents a front elevation of door embodying my invention.

Fig. 6 represents a section on line 6—6 of Fig. 7.

Fig. 7 represents a section on line 7—7 of Fig. 6.

Fig. 8 represents a front elevation on an enlarged scale, of one of the rotary tumblers.

In the drawings, 1 designates the front wall of the safe vault or the like, having hinged thereto, on the hinge 2, a vault door 3, of the usual construction. In order to secure an interlocking of the door 3 with the wall 2 of the vault at a plurality of points along the outer and contacting periphery of the door, I provide a plurality of radially disposed sliding bolts 4, slidably mounted within suitable guides 5, attached to or formed integral with the door 3. Each of the sliding bolts 4 is provided with one or more rotary tumblers 6, carried in suitable bearing openings or apertures, extending into the wall 3, in alignment with the edge or edges of the bolt 4. The bolt 4 is in turn provided with a semi-circular recess 7 in the edges thereof, in alignment with said tumbler 6, in the outer or locking position of the bolt, so as to receive said tumbler within said semi-circular recess, thereby to lock said bolt in its outer or locking position.

In order to release the bolt however, so as to permit the same to be moved inwardly into a disengaging or unlocking position, the tumblers 6 are provided with a recess extending to approximately the axis of the tumbler, in alignment with the edge of said bolt, into which recess 8 said bolt may enter, when the tumbler is so revolved as to bring the recess clearly in alignment with the bolt. Thus upon turning one or several of the tumblers into a recess 7, the bolt is fixed or locked in its position; while upon revolving the tumbler to the proper angular position so as to withdraw the same from the recesses 7, and to align the flat faces 8

of the recess with the bolt, the bolt is permitted to slide into its inner or unlocked position.

In order to permit the accurate setting of each of the tumblers 6, by sight, by any person or persons authorized to open the vault, each of the tumblers 6 is provided with a dial 9 having proper graduations thereon, which may be numbered or otherwise designated, and a knob 10, whereby the dials and

the tumblers may be turned. Thus, upon initially noting the proper positions of each of the dials, for revolving or setting the tumblers into the aligning or opening positions thereof, the tumblers may be readily set into said positions at any time by one familiar with setting the same. Furthermore it will also be seen that it requires only the mis-alignment of one of the several tumblers 6 in order to lock the bolt in its closed position.

In order permanently to secure the tumblers 6, within their proper apertures in the door, the discs or collars 11 are secured to their inner ends by means of taper pins or any other suitable fastening means, as shown in Figs. 3 and 4.

In order to move each of the several bolts 4 simultaneously and in unison with each other, and in order also to lock each and every one of the several bolts by each and every other bolt; I provide a central shaft 12 extending through the door, operated by an outer handle 13, and carrying on the inner end thereof a spider 14 having a spiral extension corresponding to each of said sliding bolts 4. Each of the limbs 15 is operatively attached to the corresponding bolt, through a loop or other guiding means 16, on the inner end of each bolt, when the spider is revolved in either direction. Thus upon turning the handle 13 in a right hand direction, in Figure 1, each of the bolts 4 will be withdrawn simultaneously; while upon revolving the bolts 4 in the reverse direction, the bolts will be extended outwardly into their locking positions. By this novel arrangement of locking bolts, it is also apparent that each of the locking bolts 4 is retained in its outer or engaging position and may not be withdrawn, until each and every one of the bolts is free to be withdrawn by the spider, since any one of the bolts may lock the spider against any rotatory movement thereof.

While in above description and the accompanying figures in the drawings, I have shown an embodiment of my invention as applied to vault doors and the like, the same is applicable to any door, closure, or the like, one form of which I have illustrated in Figs. 5-7 inclusive; in which illustrations, my novel permutation lock is applied to a door of the usual construction employed in dwellings and the like. Here the spring bolt 17 sliding within the recess 18, urged out-

wardly by the spring 19, is of any suitable construction, and preferably having a beveled outer end as is customary in spring latches. I provide a similar set of locking tumblers differing however from the foregoing construction, in having a plurality of dials on each tumbler, namely one on each end thereof, on the inside and outside of the door. In order to withdraw the bolt 17, I may provide a shaft 20 carrying the arm 21, which engages a number of pins 22 carried by the bolt, and which shaft may be revolved by any knob or handle.

It will now be apparent that I have devised a novel and useful permutation vault lock which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent is:—

1. In a device of the character stated a vault door, a plurality of radially disposed locking bolts slidably carried therein, rotatable permutation tumblers seated within said door in alignment with the edges of each of said locking bolts, a dial carried by the outer ends of said tumblers for properly positioning the same, a central operating shaft extending through the door, actuating means carried by said shaft and means carried by each of said bolts for engaging said actuating device.

2. In a device of the character stated, a vault door, a plurality of radially disposed locking bolts slidably carried therein, rotatable permutation tumblers seated within said door in alignment with the edges of each of said locking bolts, a dial carried by the outer ends of said tumblers for properly positioning the same, a central operating shaft extending through the door, a spider having a spiral arm corresponding with each bolt, carried by said shaft, and means carried by each of said bolts for engaging said spiral arms.

JOHN WINKLER.
